UNITED STATES PATENT OFFICE.

OSCAR L. OWEN, OF WHITINSVILLE, MASSACHUSETTS, ASSIGNOR TO THE WHITIN MACHINE WORKS, OF WHITINSVILLE, MASSACHUSETTS, A CORPORATION OF MASSACHUSETTS.

BOBBIN-HOLDER.

1,135,712.

Specification of Letters Patent. Patented Apr. 13, 1915.

Application filed April 18, 1913. Serial No. 761,871.

To all whom it may concern:

Be it known that I, OSCAR L. OWEN, a citizen of the United States, residing at Whitinsville, in the county of Worcester 5 and State of Massachusetts, have invented the following described Improvements in Bobbin-Holders.

The bobbin holder of this invention provides for the accommodation of more than 10 a single size of bobbin without danger of the escape of the bobbin while unwinding and thereby adapts the spooler in which it is employed, to be used for different varieties of work with the least trouble to the 15 operator.

The drawing herewith illustrates the preferred form of the invention,

Figure 1 being a side elevation, with the holder rod in section; Fig. 2 a top plan; and 20 Fig. 3 an end view with the guard lug in section.

The frame of the new holder is a bracket provided with a claw 1, and set screw, by 25 which it may be attached to the holder-rod 2 of the spooler, and with a bobbin abutment 3, and also with an overhanging arm 4, all of which parts can be conveniently made in a single piece or casting, as shown 30 in the drawings. The bobbin abutment 3, is formed by a disk-shaped enlargement of the upstanding arm of the bracket, immediately above the attachment claw 1, and provides a transversely extending surface 35 against which the base of the bobbin may rest.

The drawing shows the holder in a horizontal position, but it will of course be understood that when in use on the spooler, it is supported on the holder-rod at a slight 40 inclination which causes the base of the bobbin to bear against the smooth surface of the abutment.

The overhanging arm of the bracket is slotted for its full length and on one side 45 of the slotted part two lugs 5 are provided to hold the pintle 6 which forms the pivotal support for the bobbin-cradle. The latter is composed essentially of a cradle-pan 7, which is skeletonized, as shown, to save 50 weight, and two side limbs 8, which are apertured in alinement to receive the pintle 6, and joined at the top by a relatively massive cross-piece 9 forming a counter-weight. The upper terminals of the limbs, above the 55 pivotal axis, turn outwardly or away from

the pintle, as shown in Fig. 3, so as to gain the leverage necessary for counter-balancing the weight of the cradle-pan. The pintle 6 also carries a sleeve 10, occupying the entire space between the limbs 8, and provided 60 with a set screw 11, which thrusts against the pintle and serves as a means for securing the sleeve in different positions thereon.

On the opposite side from the cradle-pivot, the slotted overhang is provided with 65 two lugs 12, of which only one appears in the drawings, being shown in Fig. 3. These lugs are perforated to receive the ends of a wire 13, which is bent, as shown in the drawings, forming a bobbin-guard which 70 extends longitudinally of the holder from the bobbin abutment to a point well beyond the end of the cradle-pan. The lugs support this guard so that it may swing toward and from the cradle, engaging or resting 75 by gravity on the bobbin therein, but outward swinging of the guard beyond the free lip of the cradle is prevented by stop portions on the lugs 12, one of which stop portions is shown in section at 14 in Fig. 3. 80

The counterbalanced cradle and guard wire coöperate to confine the bobbin in place as the yarn is drawn from it and to maintain a substantially constant tension in the yarn, and to this end it is necessary that 85 the center of gravity of the bobbin be centralized with respect to the cradle-pan; otherwise the jumping of the bobbin as it is rapidly unwound is apt to dislodge it from the cradle. By loosening the set screw 90 11 and shifting the sleeve 10 one way or the other, the cradle is thereby shifted along its pivotal axis and toward the bobbin abutment, thereby bringing the pan in the desired position and instantly adapting the 95 holder to be used with any desired size of bobbin. The guide wire being longer than the range of lengthwise movement of the cradle, will at the same time accommodate the different bobbins without adjustment. 100 In the various adjustments of the bobbin cradle, a stop lug 15 in the form of a longitudinal rib serves to prevent outward swinging of the cradle-pan to such extent as might dump the bobbin from the holder. 105

It will of course be apparent that the precise details of the support of the cradle do not form essential features of the present invention and also that the invention is not limited to the particular proportions or di- 110

mensions of parts which have been shown in the drawings in illustration of the preferred form.

I claim:

5. 1. A bobbin holder for spoolers comprising a frame having a bobbin abutment, a counterbalanced bobbin-cradle pivotally suspended in front of the abutment and means for shifting the cradle relatively toward and from the abutment, to centralize the same relatively to bobbins of different size.
10. 2. A bobbin holder for spoolers comprising a frame having a slotted overhang, a bobbin-cradle pivotally suspended on an axis at one side of the said overhang and movable in the direction of said axis, and a fixed abutment on the frame adapted for engagement by the bobbin in the cradle.
15. 3. A bobbin holder for spoolers comprising a frame having an overhanging arm and a bobbin abutment, a bobbin-cradle pivotally suspended at one side of the arm and

capable of adjustment toward the abutment, and a guard member pivotally suspended on the opposite side of the slot adapted to 25 engage the bobbin, the said member extending in both directions beyond the extreme positions of the cradle.

4. A bobbin holder for spoolers comprising a frame adapted for support on a 30 holder-rod and having a bobbin abutment and an overhanging arm, a counterbalanced bobbin-cradle pivotally suspended from the said arm and adjustable thereon toward or from the bobbin abutment, and means for 35 securing the cradle in its adjusted position.

In testimony whereof, I have signed this specification in the presence of two witnesses.

OSCAR L. OWEN.
